Primary Examiner — Amber R Stiles*Assistant Examiner* — Christen Pilar Brown-Lorrig(74) *Attorney, Agent, or Firm* — CKC & Partners Co., LLC(57) **CLAIM**

The ornamental design for a lace tightening device dial as shown and described.

DESCRIPTION

FIG. 1 is a perspective view of a lace tightening device dial showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof shown in a condition of use.

The evenly spaced broken lines shown in the drawings represent portions of the lace tightening device dial and form no part of the claimed design. The dot-dot-dash lines shown in FIG. 8 represent environmental structure and form no part of the claimed design.
